UNITED STATES PATENT OFFICE.

HERSCHEL V. LEE, OF CHETOPA, KANSAS, ASSIGNOR OF ONE-HALF TO F. J. CUNNINGHAM, OF CHETOPA, KANSAS.

ROTARY ENGINE.

Application filed August 16, 1924. Serial No. 732,437.

The present invention relates to rotary engines, and aims to provide a novel and improved machine of that kind wherein liquid is used to provide the pistons for the 5 chambers of the rotor, thereby reducing the number of parts and friction to a minimum.

As a more specific object, the invention aims to provide a rotary internal explosion engine of novel and improved construction 10 employing the generic idea of using liquid to form the pistons of the rotor chambers.

A further object is the provision of novel mechanism for operating the valves and energizing the spark plugs or igniters of the 15 engine.

With the foregoing and other objects in view, which will be apparent as the description proceeds, the invention resides in the construction and arrangement of parts, as 20 hereinafter described and claimed, it being understood that changes can be made within the scope of what is claimed, without departing from the spirit of the invention.

The invention is illustrated in the accompanying drawings, wherein—

Figure 1 is a median diametrical section of an internal combustion engine embodying the improvements, portions being shown in elevation.

30 Figs. 2, 3 and 4 are sections taken on the respective lines 2—2, 3—3 and 4—4 of Fig. 1.

The engine includes a rotor 11 and a casing 12 in which the rotor is housed. The 35 rotor 11 comprises the rim 13, preferably of cylindrical form, partitions 14 extending radially outward from the rim 13, and the side plates 15 and 18 extending beyond the rim. As shown, there are five partitions 14 which, with the side plates, form the chambers A, B, C, D and E which are open at 40 the circumference of the rotor.

The side plate 15 of the rotor has a hub 16 keyed or otherwise secured on a shaft 17 disposed in the axis of the rotor and projecting into the rotor from the exterior, and the side plate 18 has a hub 19 mounted for rotation on a journal member 20 which is 45 also arranged in the axis of the rotor and which projects into the rotor from the side opposite to the shaft 17, the adjacent ends of the shaft and member 20 preferably abutting and having a pivot joint to assist in

supporting the inner end of the shaft. The rotor is thus supported by the shaft 17 and 55 journal member 20.

The casing 12 comprises the side plates 21 and 22, and the rim 23 which is integral with the side plate 21 as shown, the side plate 22 being detachably secured to the rim 23, as at 24, for convenience in assembling and separating the parts. The side plate 22 has a hub 25 mounted for rotation on an eccentric portion 26 with which the member 20 is provided, and the side plate 21 has a hub 27 mounted for rotation on an eccentric portion 28 of a journal and bearing member 29. The shaft 17 is journaled through the member 29, while the side plate 21 is rotatable around the eccentric portion 28 of said member 29. The eccentric portions 26 and 28 of the journal members are concentric relatively to the casing 12 and are eccentric relatively to the rotor, the rotor and casing being eccentric with reference to one another. As shown, the eccentric portions 26 and 28 extend downwardly so that the rotor and rim of the casing are closest to one another at the top. The casing is 70 free to rotate around the members 20 and 29, and the hubs 25 and 27 bear against the hubs 16 and 19 so as to prevent axial displacement of the casing.

The members 20 and 29 are rigidly supported by a suitable frame or support (not shown) so as to be non-rotatable, although the casing can rotate freely around said members.

Other than the contact between the hubs of the rotor and casing there are no solid parts having frictional contact between the rotor and casing, so that pistons of solid material are entirely eliminated, thereby reducing friction and working parts to a minimum. Instead, water 30 or other liquid is contained within the casing and, when the engine is in operation, such liquid forms the pistons for the chambers of the rotor. The liquid, when the rotor is rotated at a sufficiently high speed, is thrown outward around and away from the axis of rotation by centrifugal force, thereby providing a ring of liquid within the casing along the rim thereof into which the partitions 14 and side plates 15 and 18 extend so that the liquid enters the chambers to form the pis-

tons thereof. The depth of the "liquid ring" will be substantially uniform owing to the fact that the centrifugal force will overcome gravity and will throw the liquid outwardly in all radial directions with equal force, so that the liquid is distributed uniformly around the axis of rotation along the rim of the casing. The liquid ring will rotate with the rotor, and the casing being free to turn can also rotate with the rotor and liquid ring, so that the rotor, liquid ring and casing can all rotate as a unit. However, the rotor and casing being eccentric will result in the inner periphery of the liquid ring and rim 13 of the rotor being eccentric, the top of the rim being closer adjacent to the inner periphery of the liquid ring than the bottom of the rim 13, thus resulting in the spaces between the liquid ring and rim 13 or bottoms of the chambers decreasing in size when approaching the top and increasing in size when approaching the bottom, as clearly apparent by reference to Fig. 3.

25 By using the liquid ring between the rotor and casing this will eliminate all mechanical parts between the rotor and casing, as well as reducing the friction to a practically negligible minimum as compared with the friction between solid parts.

The rim 13, which forms the bottoms of the rotor chambers, has the intake ports 31^a, 31^b, 31^c, 31^d and 31^e and the exhaust ports 32^a, 32^b, 32^c, 32^d and 32^e opening into the respective chambers A, B, C, D and E, and the respective poppet valves 33^a, 33^b, 33^c, 33^d and 33^e and corresponding valves 34^a, 34^b, 34^c, 34^d and 34^e are seatable against the rim 13 over the corresponding intake and exhaust ports. The rotor has passages 35 parallel with the axis of rotation extending through the side plate 18 to the annular space between the side plate 18 of the rotor and the side plate 22 of the casing, and an exhaust pipe or conduit 36 extends through the eccentric 26. Thus, exhaust gases discharged through the exhaust ports will flow through the passages 35 into the space between the side plates 18 and 22 and then through the pipe or conduit 36. The rotor is further provided with intake passages 38 leading from the intake ports parallel with the axis of rotation to an annular space 37 with which the rotor is provided adjacent to the side plate 18, so that carbureted air or other explosive gas delivered into the space 37 can flow through the passages 38 and intake ports when the intake valves are opened. In order to supply the explosive gas to the space 37, the member 20 has a chamber 39 into which the gas flows by way of the pipe or conduit 40 which is attached to the member 20 on the exterior of the casing. The member 20 has an opening 41 establishing communication between the chamber 39 and

space 37 so that the carbureted air or other explosive gas is supplied to the intake passages 38.

The exhaust and intake valves have the respective inwardly extending stems 42 and 43, arranged radially of the structure, and the rotor has inwardly extending guides 44 through which the stems are slideable. Coiled springs 45 surround the guides 44 and bear against spring seats 46 secured to the stems, thereby yieldingly moving the valves inwardly to seated position.

The valves are unseated or opened outwardly by the provision of cams 48 and 49, respectively, on a sleeve 47 that is rotatably mounted on the shaft 17 within the rotor between the member 20 and side plate 15. A pair of cams 48 and a pair of cams 49 are similarly arranged, the cams of each pair being diametrically opposite to one another.

In order to time the opening and closing of the valves, the sleeve 47 is rotated in the direction of rotation of the rotor at a speed one-fourth faster than the speed of rotation of the rotor. Thus, the sleeve 47 is formed with a gear wheel 50 at that end adjacent to the member 20, and said gear wheel meshes with a pinion 51 that is rotatable on a pintle 52 carried by an arm 53 with which the member 20 is provided. A pinion 54 is integral

as a unit with the pinion 51, and is of smaller diameter, and meshes with a gear wheel 55 of larger diameter than the gear wheel 50. The gear wheel 55 is keyed or otherwise secured on the shaft 17 and is of a diameter one-fourth larger than the diameter of the gear wheel 50, so that while the shaft 17 makes a complete revolution, the sleeve 47 will have made one and one-fourth revolutions. The fractional additional movement of the sleeve 47 with reference to the rotor corresponds with the number of rotor chambers, as will be apparent as the invention is more fully understood from the following description.

The chambers A, B, C, D and E have the respective spark plugs or igniters 56^a, 56^b, 56^c, 56^d and 56^e which are engaged outwardly through the rim 13 for igniting the explosive gas in said chambers.

A commutator is provided for connecting the spark plugs in the ignition circuit in proper firing order, and comprises a disk 57 secured to the side plate 15 of the rotor around the sleeve 47, and provided with a rim 58 within which are disposed the annular series of arcuate contact segments 59^a, 59^b, 59^c, 59^d and 59^e for the respective chambers. The rim 58 has the binding posts 60 connected to the segments, said binding posts and segments being insulated from one another and from the metal parts of the engine, and the binding posts 60 are connected by wires 61 with the corresponding spark plugs. Thus, one electrode of each plug is

connected to the corresponding segment of the commutator while the other electrode is grounded to the metal parts of the engine, in accordance with standard ignition practice. The timing sleeve 47 for the valves and ignition has the diametrically opposite radial arms 62 on which are secured the insulated contact brushes 63 and 63' that slide along the segments, and the brushes are connected by wires 64 with insulated contacts 65 and 65', respectively, which are carried by the sleeve 47.

The contacts 65 and 65' form a part of the ignition timer, and such timer includes a brush 66 past which the contacts 65 and 65' are movable. The brush 66 is carried by an offset arm 67 of an insulated rod 68 disposed in the axis of rotation of the rotor. The rod 68 extends through the member 20, and said member 20 has an arcuate slot 69 through which the arm 67 of the rod extends, so that said rod can be turned to change the angular position of the arm 67 and brush 66; thereby enabling the sparks to be timed, for advancing and retarding the sparks. The rod 68 is insulated so as not to be in electrical connection with the member 20 or other metal parts of the engine, such metal parts and rod 68 completing the electrical ignition circuit which is supplied by the high potential current from a suitable magneto or other source of energy (not shown).

The wires 61 and 64 are preferably arranged close adjacent the sleeve 47, so as not to be thrown outwardly by centrifugal force, inasmuch as this would possibly interfere with other parts.

In starting the engine, the rotor is rotated at a sufficiently high speed, so that the liquid in the casing assumes its ring form, the liquid being rotated with the rotor. The gaseous fuel is then admitted through the pipe 40, and the ignition circuit is closed, to start the power impulses. The rotor turns clockwise as seen in Fig. 3 and counter clockwise as seen in Figs. 2 and 4, as indicated by the arrows. The engine operates under the four cycle principle, there being an explosion in each chamber of the rotor for each two revolutions. In other words, for each chamber of the rotor one-half of a revolution is used for the intake of gas, the next one-half of a revolution is used for compression, the third one-half revolution used for the explosion or power impulse, and the fourth one-revolution used for the exhaust of the burnt gas. By using the five chambers there are five explosions or power impulses for every two revolutions of the rotor. As shown in Figs. 2, 3 and 4, the intake valve 33^a of the chamber B and the exhaust valve 34^a of the chamber E are opened by the corresponding cams 48 and 49, and the other valves are all closed. For convenience, the half-circle movements of the chambers will

be termed strokes, in comparison with the strokes of ordinary reciprocating piston engines. With the parts as shown in Figs. 2, 3 and 4, the chamber A is starting its explosion or power strokes, the chamber B is moving through its intake stroke with the intake valve open, the chamber C is completing its explosion or power stroke, the chamber D is moving through its compression stroke, and the chamber E is completing its exhaust stroke. The firing order of the rotor chambers, A, D, B, E and C. In other words, the explosions occur in the alternate chambers, and by the provision of an odd number of chambers, two revolutions of the rotor will include an explosion in each chamber of the rotor. The chamber A, in which the gas has been compressed, has its spark plug 56^a energized. Thus, the brush 63 contacts with the segment 59 connected to the spark plug 56^a, and the contact 65 engages the brush 66 at the proper time to ignite the charge in the chamber A. The expansive force of the burning gas in the chamber A has a tendency to enlarge the space between the water ring and rim 13 of the rotor, thereby exerting a torque upon the rotor which will turn it, the space between the water ring and rim 13 becoming larger as the chamber A moves downwardly. There is of course a tendency for the burning gas to force the liquid out of the chamber A, but this is resisted by the fact that the centrifugal force tends to maintain the liquid ring of uniform depth throughout, especially when the rotor and liquid ring revolve at a sufficiently high speed. This will assure against excessive distortion of the inner periphery of the liquid ring under the force of the explosions, as well as under the compression of the gas in the chambers. The power of the explosions is thus directed against the rotor for turning same. Now, by the time the chamber A reaches the bottom or the end of its explosion stroke, the contact 65 will have moved from the brush 66, and the power of the explosion will have been spent in turning the rotor. Then, as the chamber A moves upwardly through its exhaust stroke, the corresponding cam 49 will have advanced sufficiently far ahead to open the exhaust valve 34^a of the chamber A, in the same manner that the cam is opening the exhaust valve of the chamber E as seen in Fig. 2, it being kept in mind that the sleeve 47 rotates faster than the shaft 17 and rotor. The space in the chamber A growing smaller during the exhaust stroke, will result in the products of combustion being forced out through the exhaust port 34^a. When the chamber A has again reached the top position, at the end of one revolution, the cam 49 which opened the exhaust valve 34^a will have moved on, so that said valve is released and closed by its spring. Then,

when the chamber A starts to move downwardly the second time through its intake stroke, the corresponding cam 48 will have been advanced sufficiently far to open the intake valve 33^a of the chamber A. The cam 48 which so opens the valve 33^a is the one at the left in Fig. 3, said cam having passed and opened the intake valve 33^a of the chamber E in the meantime. Thus, the valve 33^a being opened, will permit the gas to be drawn into the space of the chamber A as said space increases in size during the downward movement of said chamber A, and the intake valve 33^a is closed when the chamber reaches the end of its intake stroke, the corresponding cam 48 having moved past the valve 33^a so that said valve is released and closed by its spring. Then, as the chamber A again moves upwardly through its compression stroke, both valves of said chamber remain closed, and the gas in the chamber is compressed owing to the reduction in size of the space between the water ring and rim 13 of the rotor. The chamber A then reaches the starting position of its explosion stroke, to complete the two revolutions, and the operation, with reference to the chamber A is then repeated as before. The same applies to each chamber of the rotor, and during the time that the chamber A has made two revolutions and completed its explosion, exhaust, intake and compression strokes, each of the other chambers completed its four cycle operation in the same manner.

Referring to Fig. 4 wherein the brush 66 engages the contact 65, and the brush 63 engages the segment 59^a of the spark plug 56^a, the forward motion of the sleeve 47^a with reference to the rotor will bring the brush 63' against the segment 59^d while the brush 63 is moving away from the segment 59^a, thereby connecting the spark plug 56^d of the chamber D with the timer, and when the chamber D reaches firing position (which is the position of the chamber A as shown in Figs. 2, 3 and 4), the contact 65' will engage the brush 66, with the brush 63' engaging the segment 59^a. Then, as the brush 63' is removed from the segment 59^d, the brush 63 rides along the segment 59^b, and when the chamber B reaches firing position, the contact 65 will engage the brush 66 thereby igniting the spark plug 56^b. Thus, as the rotor revolves, the brushes 63 and 63' move faster than the segments of the commutator, thereby connecting the spark plugs of alternate chambers in the circuit in succession, so that the timer will close the spark plug circuits in proper order.

Referring to Fig. 2, showing the exhaust valves, the right hand cam 49 has opened the exhaust valve 34^e of the chamber E. Now, as the sleeve 47 turns faster than the rotor, the left hand cam 49 will open the exhaust valve 34^c of the chamber C when the cham-

ber C moves upwardly. Then, the opposite cam 49, which previously opened the valve 34^e, will advance and open the valve 34^a of the chamber A as such chamber reaches and moves through its exhaust stroke. Thus, as the cams 49 move faster than the rotor, they will open the exhaust valves of the alternate chambers in proper order.

Referring to Fig. 3 showing the intake valves, the right hand cam 48 has opened the intake valve 33^b of the chamber B. Now, when the chamber B is completing its intake stroke, the sleeve 47 rotating faster than the rotor, will result in the valve 33^b being released and seated, and the opposite cam 48 opens the intake valve 33^e of the chamber E by the time said chamber has reached and is moving through its intake stroke. Then follows the opening of the intake valve 33^c of the chamber C, the opening of the intake valve of the chamber A and the opening of the intake valve of the chamber D in succession.

It will therefore be seen that the timing sleeve 47 is rotated at a speed sufficiently faster than the speed of the rotor so as to open the intake and exhaust valves and close the circuits of the spark plugs or igniters in proper order and during the corresponding strokes of the chambers so that the engine will operate as described.

By turning the rod 68 so as to move the brush 66 forwardly or rearwardly with reference to the direction of rotation of the rotor, the sparks can be retarded or advanced, as will be apparent. As shown in Fig. 4, with the brush 66 in the position shown, the spark plugs will be energized just as they pass over the axis of rotation and start to move downwardly. However, the brush 66 can be moved forwardly and rearwardly so as to change the timing of the sparks, in order to obtain maximum power and efficient operation of the engine.

By eliminating solid reciprocating or oscillatory solid pistons, this will not only eliminate structural parts to simplify the construction, but will also eliminate the greater part of the friction which exists in engines using such pistons. The liquid ring of the present engine will involve negligible friction, the rotor, liquid ring and casing all rotating as a unit, and the only friction is the turning movement of the rotor and casing on their supports and the slight radial movement of the circumferential portions of the rotor into and out of the liquid ring, but such friction is practically negligible as compared with the friction and resistance offered by solid reciprocating or oscillating pistons.

Having thus described the invention, what is claimed as new is:—

1. A rotary internal combustion engine comprising a casing, a rotor therein having

chambers with intake and exhaust ports for each chamber, liquid within the casing forming, by centrifugal action, when the rotor is revolved a liquid ring providing pistons for 5 said chambers, rotor-carried valves normally closing said ports, rotor-carried igniters for said chambers, and means operably connected to the rotor to rotate at a different speed than the rotor and controlling said valves 10 and igniters to time the opening of the valves and operation of the igniters.

2. A rotary internal combustion engine comprising a casing, a rotor therein having chambers and intake and exhaust ports for 15 each chamber, liquid within the casing forming, by centrifugal action, when the rotor is revolved a liquid ring providing pistons for said chambers, said rotor being mounted eccentrically within the casing so that the liquid 20 pistons move into and out of the chambers as the rotor revolves, rotor-carried valves normally closing said ports, rotor-carried igniters for said chambers, and means operably connected to the rotor to 25 rotate at a different speed than the rotor and controlling said valves and igniters to time the opening of the valves and operation of the igniters.

3. A rotary internal combustion engine 30 comprising a casing, a rotor mounted therein and having an odd number of chambers with intake and exhaust ports for each chamber, liquid within the casing forming, by centrifugal action, when the rotor is revolved a liquid ring providing pistons for 35 said chambers, rotor-carried igniters for said chambers, rotor-carried valves normally closing said ports, and means operably connected to the rotor to rotate at a different 40 speed than the rotor and controlling said valves and igniters to open the valves and operate the igniters of alternate chambers in timed relation.

4. A rotary internal combustion engine 45 comprising a casing, a rotor mounted eccentrically therein and having open chambers at its circumference and intake and exhaust ports for each chamber, liquid within the casing forming, by centrifugal action, when 50 the rotor is revolved a liquid ring providing pistons for said chambers so that the liquid pistons move into and out of said chambers as the rotor revolves, rotor-carried valves normally closing said ports, rotor-carried 55 igniters for said chambers, there being an odd number of chambers, and means operably connected to the rotor to rotate at a different speed than the rotor and controlling said valves and igniters to open the valves 60 and operate the igniters of alternate chambers in timed relation.

5. A rotary internal combustion engine comprising a casing, a rotor mounted eccentrically therein and having chambers with 65 intake and exhaust ports for each chamber,

liquid within the casing, forming, by centrifugal action, when the rotor is revolved a liquid ring providing pistons for said chambers so that the liquid piston of each chamber moves into and partly out of the chamber during successive half-revolutions of the rotor, rotor-carried intake and exhaust valves for each chamber normally closing said ports, a rotor-carried ignitor for each 70 of said chambers, and mechanism controlling the opening of said valves and the operation of the igniters arranged to provide a four-cycle operation as described, to provide in each chamber the opening of the intake valve, compression, operation of the 75 ignitor and opening of the exhaust valve in four successive half-revolutions of the rotor.

6. A rotary internal combustion engine comprising a rotor having chambers with intake and exhaust ports for each chamber, means for enlarging and reducing the spaces of said chambers as the rotor revolves, rotor-carried valves closing said ports, rotor-carried igniters for said chambers, and means operably connected to the rotor to rotate at a different speed than the rotor and controlling said valves and igniters to time the opening of the valves and operation of the igniters.

7. A rotary internal combustion engine comprising a rotor having an odd number of chambers with intake and exhaust ports for each chamber, means for enlarging and reducing the spaces of said chambers as the rotor revolves, rotor-carried valves closing said ports, rotor-carried igniters for said chambers, and means operably connected to the rotor to rotate at a different speed than the rotor and controlling said valves and igniters to open the valves and operate the 105 igniters of alternate chambers in timed relation.

8. An internal combustion engine comprising a rotor having chambers with intake and exhaust ports for each chamber, means for enlarging and reducing the spaces of said chambers as the rotor revolves, rotor-carried valves closing said ports, rotor-carried igniters for said chambers, a rotary member concentric with the rotor and geared 110 to the rotor to rotate at a different speed than the rotor, said member having cams for opening the valves in timed relation by the relative rotation of said member and rotor, a commutator having a part carried by the rotor connected to the igniters and a part carried by said member for connecting the igniters in an ignition circuit in timed relation, and an ignition timer connected to the 115 commutator, part of said timer being carried by said member.

9. A rotary internal combustion engine comprising two non-rotatable members, a shaft extending through one of said members, a rotor secured on said shaft and hav- 120

ing chambers and intake and exhaust ports for each chamber, means for enlarging and reducing the spaces of said chambers as the rotor revolves, rotor-carried valves closing 5 said ports, rotor-carried igniters for said chambers, a sleeve rotatable on said shaft within the rotor, gearing connecting said shaft and sleeve for rotating the sleeve at a different speed than the rotor, part of said 10 gearing being carried by the other member, said sleeve having means for opening the valves in timed relation as the sleeve and rotor rotate relatively to one another, and a commutator and timer for said igniters having 15 portions carried by the rotor and sleeve for closing the circuits of said igniters in timed relation.

10. A rotary internal combustion engine comprising two supporting members having 20 eccentric portions, a casing rotatable around said eccentric portions, a shaft passing through one of said members eccentric relatively to the casing, a rotor in said casing secured to said shaft and having chambers 25 and intake and exhaust ports for each chamber.

ber, liquid in the casing movable with the rotor by centrifugal action to form a liquid ring providing pistons for said chambers, rotor-carried valves closing said ports, rotor-carried igniters for said chambers, a sleeve 30 rotatable on said shaft within the rotor and having cams for opening said valves in timed relation by the relative rotation of said sleeve and rotor, gearing connecting said sleeve and shaft for rotating the sleeve at a 35 different speed than the rotor, part of said gearing being carried by the other supporting member, a commutator including segments carried by the rotor and connected to the igniters, said commutator including 40 brushes carried by the sleeve engaging the segments for connecting the igniters in the ignition circuit in timed relation, and an ignition timer including contacts carried by the sleeve and connected to said brushes, said timer including an adjustable brush for the engagement of said contacts.

In testimony whereof I hereunto affix my signature.

HERSCHEL V. LEE.
